(54) **SPRING, FOR CLOCKS**

(76) Inventor: **James S. Ives**

Joseph Stow's Testimony
Letters Patent:

The Schedule referred to in these Letters Patent, and making part of the same containing a description in the words of the said Joseph Stow himself of his improvement in the safety or composition main-spring for Clocks.

To all persons to whom these presents shall come: Joseph Stow of Bristol in the County of Hartford and State of Connecticut, sends greeting: Is it known that the said Joseph Stow have invented, constructed made and applied to use a new and useful improvement in the making and construction of main-springs for clocks, & to be moved by main-springs called a Safety or composition metal spring in Clocks? This improvement consisting in substituting brass or brass or composition metal in making main-springs for Clocks instead of Steel. That is, that main-springs are made of brass or composition metal ^{instead of Steel} & are made and used on such main-springs. The main-springs are made in the same shape and form as Steel, only brass or composition metal is substituted for Steel. The Inventor has made use of brass only in making such main-springs, but he considers and contemplates that other composition metals may be used for that purpose. He does not claim the invention of main-springs for clocks, but the application of brass or composition metal instead of Steel for such main-springs, and for this he claims a patent. The advantage and benefit of this improvement is that main-springs can be made much easier and cheaper of Brass or other like metal than of Steel, and equally as good.

For testifying that the above is a true specification of my said improvement as above described & have
